UNITED STATES PATENT OFFICE.

HARRY DOLAND, OF NORTH ATTLEBORO, MASSACHUSETTS, ASSIGNEE TO PAYE & BAKER MANUFACTURING COMPANY, OF NORTH ATTLEBORO, MASSACHUSETTS, A CORPORATION OF MASSACHUSETTS.

CRUMB SWEEPER.

1,402,343.

Specification of Letters Patent.

Patented Jan. 3, 1922.

Application filed April 21, 1920. Serial No. 375,532.

To all whom it may concern:

Be it known that I, HARRY DOLAND, a citizen of the United States, residing at North Attleboro, in the county of Bristol, State of Massachusetts, have invented certain new and useful Improvements in Crumb Sweepers, of which the following is a specification.

My invention relates to improvements in crumb-sweepers for cleaning food particles or crumbs from tables.

One object of the invention is to provide a relatively light, simple device for the purpose specified which will be easier and more convenient to operate and more efficient in use.

Another object of the invention is to render the sweeper automatic in its operation of sweeping up the crumbs, and also more convenient to empty and clean by providing automatic means for dumping its contents.

Other objects of the invention will appear from the detailed description of the device contained in the following specification which is illustrated by the accompanying drawings. In the drawings:

Fig. 1 is a plan view of my improved crumb-sweeper showing the top of its casing as partly broken away to disclose the arrangement of the dumping crumb trays on its interior;

Fig. 2, a side elevation of the device shown in section on the line A—A of Fig. 1;

Fig. 3, a similar sectional view taken on the line B—B of Fig. 1 and illustrating the crumb-trays as released or in dumping position.

Referring to the drawings, my improved crumb-sweeper comprises essentially a casing 2 of substantially oblong shape having a crowned top 3, square ends 4, and a handle 5 on its side. Rotatably mounted within the casing 2 is a cylindrical crumb-brush 6 carried by rollers or wheels 7 at its opposite ends. The brush 6 may be of any suitable type and as herein shown is constructed with an axial spindle 8 formed of twisted wire in which are held a series of bristles 9 projecting radially therefrom and trimmed to a cylindrical contour on the periphery of the brush. The ends of the spindle 8 are driven into the axial bores 10 of the end rollers 7 and the latter carry rubber tires 11 to adapt them to roll smoothly over the

table 1 to revolve the brush thereagainst, see Fig. 2. The wheels or rollers 7 are journaled to the ends 4 of the casing 2 by means of screws 12 engaging their bores 10. As shown in Fig. 1, the screws 12 are screwed through bosses or hubs 13 on the ends of the casing 2 and are formed with reduced extremities 14 on which the rollers rotate.

It will be observed by reference to Figs. 2 and 3 that the casing 2 is constructed with an open bottom, and at either side of the crumb-brush 6 are pivotally mounted crumb-trays 15. The trays 15 slope upwardly away from the brush 6 and the ends 4 of the casing 2 are cut away at an angle on the bottom, both back and front, to adapt the sweeper to be rocked slightly on the axis of the wheels 7. The forward sides of the trays 15 extend in adjacent, parallel relation with the periphery of the brush 6 and are provided with sloping ledges or guards 16 across which the crumbs are swept into the trays. At their rearward sides the trays 15 are provided with upwardly curved marginal ledges or rims 17 which fit within the downturned sides of the top of the casing 2. The opposite ends of the trays 15 are closed by transverse rims 18.

The trays 15 may be pivoted to the ends 4 of the casing 2 by means of pins or pintles 20, or through any other suitable connections. As illustrated in Fig. 1, the pins 20 are provided with heads at one end and are inserted through holes in the end-pieces 4 of the casing 2 with their opposite ends driven into hubs or sleeves 21 secured to the trays 15. In this way the pins 20 are held fast in the trays 15, or they might be soldered or otherwise secured thereto, while being adapted to turn in their bearings in the end-pieces 4. This arrangement provides hinged joints between the crumb-trays and the casing to allow the trays to drop down into the position shown in Fig. 3 to dump their contents in the manner and for the purpose as later explained.

The trays 15 are held in cooperative relation with the brush 6 by means of automatically-operated latches as next described. Fastened to the depending sides of the top of the casing 2 are loops 22 which may be formed of wire soldered in place at the ends, or constructed in any other suitable manner. The loops 22 are adapted to be en-

gaged by spring latches 23 which may be constructed of wire and soldered to the upturned sides of the trays 15. If preferred, the latches 23 might be made of sheet-metal, or of any other construction, their upper ends being formed with notches 24 adapted to snap around the loops 22 on the casing.

Having now described the construction and arrangement of my improved device in 10 detail its methods of operation will next be explained. Normally the crumb-trays 15 are held in closed relation, as illustrated in Fig. 2, and by grasping the handle 5 the operator moves the sweeper back and forth 15 over the table T or the cloth covering the same. The sweeper is supported on the rollers or wheels 7 and as the latter roll along the table T the brush 6, connected with the wheels, will be revolved in one direction 20 or the other with its bristles brushing across the top of the table. In this manner any crumbs or particles of food on the table will be swept up across the inclined guards 16 on the sides of the crumb-trays 15 and deposited within the trays. By passing the sweeper back and forth across the surface to be cleaned the crumbs or other particles are quickly gathered up and when it is desired to empty the accumulation it is a very 30 simple matter as follows: To dump the crumb-trays 15 the sweeper is held over a waste receptacle and the trays allowed to drop downwardly as illustrated in Fig. 3. To release the trays it is only necessary to 35 press on the opposite sides of the casing 2 to disengage the loops 22 from the latches 23. This is accomplished most conveniently by holding the casing of the sweeper in the hand with the thumb and fingers pressing 40 against its opposite sides. A slight pressure of the fingers is sufficient to spring the sides of the casing 2 inwardly whereby to release the loops 22 from the notches 24 in the latches 23, and the trays 15 will then 45 drop by gravity to empty their contents. After the sweeper has been cleaned in this manner to prepare it for operation again it is only necessary to swing the trays 15 back into closed relation and their latches 23

will automatically lock with the detent 50 loops 22 to hold them in place.

It will be observed that my improvement provides a particularly simple and efficient device for the purpose specified, and that its operation is automatic both in its function of sweeping up crumbs, and as regards its self-dumping or emptying feature. Various modifications might be made in the form and structure of the device without departing from the spirit or scope of the invention and therefore I do not wish to limit my claims to the exact embodiment herein shown.

I claim and wish to secure by Letters Patent of the United States:

1. In a crumb-sweeper, the combination of a sheet-metal casing having an arched top adapted to be grasped on its sides between the thumb and fingers of the hand, a rotary brush in said casing, crumb-trays 70 hinged to the casing to allow them to drop to empty their contents, and detent-means on the inside of the casing arranged to hold the trays in close relation therewith, said detent-means adapted to be released by the 75 pressure of the thumb and fingers against the sides of the casing.

2. In a crumb-sweeper, the combination of a spring-metal casing, a rotary brush in the casing, crumb-trays hinged to the casing to allow them to drop to empty their contents, and detent-means on the sides of the casing for maintaining the trays in operative relation, said detent adapted for release by pressure on the sides of the casing 80 to release the trays to allow them to drop.

3. In a crumb-sweeper, the combination of a spring-metal casing having resilient sides, a rotary brush in the casing, crumb-trays hinged to the casing to allow them to 90 drop to empty their contents, latches for holding the trays in operative position, and detents on the sides of the casing for engaging the latches, said detents adapted to be released from the latches by springing the 95 sides of the casing inwardly.

In testimony whereof I affix my signature.
HARRY DOLAND.
